US00D573143S

(12) **United States Design Patent**
Park et al.

(10) **Patent No.:** US D573,143 S
(45) **Date of Patent:** ** Jul. 15, 2008

(54) **PORTABLE TERMINAL**

(75) Inventors: **Hyoung-Shin Park**, Seoul (KR);
Sang-Min Hyun, Seoul (KR)

(73) Assignee: **Samsung Electronics Co., Ltd.**, Suwon,
Kyunggi-do (KR)

(**) Term: **14 Years**

(21) Appl. No.: **29/288,859**

(22) Filed: **Jun. 25, 2007**

(51) **LOC (8) Cl.** 14-02

(52) **U.S. Cl.** D14/341

(57) **CLAIM**

The ornamental design for a portable terminal, as shown and described.

DESCRIPTION

FIG. 1 is a top front perspective view of a portable terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
